UNITED STATES PATENT OFFICE.

HENRY FRANCIS SPURR, JR., OF BOSTON, MASSACHUSETTS.

AUXILIARY PEDAL FOR PIANOS.

SPECIFICATION forming part of Letters Patent No. 628,963, dated July 18, 1899.

Application filed October 12, 1898. Serial No. 693,339. (No model.)

To all whom it may concern:

Be it known that I, HENRY FRANCIS SPURR, Jr., of Boston, in the county of Suffolk, State of Massachusetts, have invented a new and efficient Auxiliary Pedal for Pianos, of which the following is a specification.

The object of my invention is to enable children to efficiently operate the pedals of a piano while at the same time allowing the position of the operator to be that the best to manipulate the keyboard of the piano and the most convenient to operatively control the piano, which I attain in the following manner:

Figure 1 is a side view of my invention. Fig. 2 is a plan view. Fig. 3 is a perspective view of my invention.

A represents the foot-rest portion of my invention, which has the piano-contacting portion *a*, the forked arm portion *a'*, and the horizontal holes *a*² and *a*³ and the opening *a*⁴.

B denotes the pedal-adjuster, which has the lever-holes *b* and *b'* therethrough, the adjusting-holes *b*², and the retaining-teeth *b*³.

C represents the removable adjusting-pin, which retains the pedal-adjuster by being passed through the hole *a*³ of the foot-rest fork and the respective adjusting-hole through the pedal-adjuster.

D denotes the fixed adjuster-retaining pin, which passes through the hole *a*³ through the foot-rest fork and is retained fixedly therein.

E represents the foot-pedal, which has the pins *e* and *e'* passing therethrough, the former to freely connect the foot-pedal to a connecting-rod and the latter to freely connect the foot-pedal to the pedal-adjuster, as shown in the drawings.

F denotes the piano-pedal-operating arm, which is pivoted to the pedal-adjuster by the pin *f* and which has its other end freely connected to a connecting-rod by the pin *f'*.

G represents the connecting-rod, which connects the auxiliary foot-pedal to the piano-pedal-operating arm that contacts the piano-pedal, which is represented by the dotted lines shown in Fig. 1 and by the numeral 1.

2 denotes the body of the piano.

The use and operation of my invention are as follows: When a person cannot conveniently operate the pedals of a piano while retaining that position essential to grace and efficient manipulation of the keyboard, by po-

sitioning my auxiliary foot-pedal so as to place the piano-pedal-operating arm over and in contact with the upper surface of the piano-pedal the operator can readily and conveniently control the piano-pedals, while at the same time retaining the essential position necessary to efficiently manipulate the piano. By withdrawing the pin *C* the pedal-adjuster 55 can be either raised to a higher position or otherwise, according to the will of the operator. In order to change the height of the auxiliary pedal and to secure such position after withdrawing the pedal-adjuster pin, all 60 that has to be done is to cause the teeth of the adjuster to engage both sides of the fixed adjuster-retaining pin according to the elevation desired of the auxiliary pedal, and then after such positioning pass the movable 65 adjuster-retaining pin through both the fork of the foot-rest portion of my invention and the pedal-adjuster, which becomes fixed in its position. The piano-engaging arm *a* passes underneath the piano and prevents the body 70 of my invention tilting or swinging or moving from its position when being operated by the foot—that is, the auxiliary pedal is thus made fixed in position. By pressing down the auxiliary pedal the connecting-rod transmits 75 the movement to the piano-pedal-operating arm and such operates the piano-pedal, and the mechanism controlling the piano-pedal causes the auxiliary pedal to return to its normal position when the foot is removed from 80 off the auxiliary pedal.

Having described my invention, I claim—

1. An auxiliary piano-pedal consisting of a foot-rest having an arm to contact the piano to retain the foot-rest body in position, and 90 provided with a forked arm extending from the body, a pin passing through the forked-arm portion of the body and being fixed thereto, a removably-fitted pin passing through the forked arm, an auxiliary pedal-adjuster 95 entering the space of the forked arm, a series of notches provided on the edge of the pedal-adjuster and engaging the fixed pin, a series of holes opposite the notches through the adjuster and engaging the removably-fitted pin, 100 a piano-pedal-operating arm having one end freely connected to the lower end of the adjuster, a connecting-rod having its lower end freely connected to the opposite end of the

piano-pedal-operating arm, and an auxiliary pedal being connected to the upper end of the adjuster, and having its opposite end freely connected to the upper end of the connecting-rod, substantially as and for the purpose described.

2. In an auxiliary piano-pedal, a foot-rest having an arm to contact the piano to retain the foot-rest body in its position, and a forked arm extending from the body, in combination with a pin passing through the forked arm and being fixed thereto, a removably-fitted pin passing through the forked arm, an auxiliary pedal-adjuster entering the space of the forked arm, teeth provided on the edge of the pedal-adjuster and the adjuster thus engaging the fixed pin, holes respectively opposite the teeth-notches through the adjuster,

and the adjuster thus engaging the removably-fitted pin, a piano-pedal-operating arm having one end freely connected to the lower end of the adjuster, a connecting-rod having its lower end freely connected to the opposite end of the piano-pedal-operating arm, and an auxiliary pedal being connected to the upper end of the adjuster, and having its opposite end freely connected to the upper end of the connecting-rod, substantially as described.

In testimony whereof I have hereunto set my hand to this application this 18th day of 30 August, A. D. 1898.

HENRY FRANCIS SPURR, JR.
